Primary Examiner — Brandon M Rosati*Assistant Examiner* — Marissa J Cash(74) *Attorney, Agent, or Firm* — Dan DeLaRosa(57) **CLAIM**

The ornamental design for a rotary flying toy, as shown and described.

DESCRIPTION

FIG. 1 is a front perspective view of the rotary flying toy of the present invention showing my new design;
FIG. 2 is front side elevational view thereof;
FIG. 3 is a back side elevational view thereof;
FIG. 4 is a side elevational view thereof;
FIG. 5 is another side elevational view thereof;
FIG. 6 is a top plan view thereof; and,
FIG. 7 is a bottom plan view thereof.
In the drawings, the broken lines depict environmental subject matter only and form no part of the claimed design.

1 Claim, 5 Drawing Sheets(56)
